(57) **CLAIM**

The ornamental design for a table top surface and edge, as shown and described.

DESCRIPTION

FIG. 1 is an upper perspective view of a table top surface and edge;

FIG. 2 is a top view of the table top surface and edge shown in FIG. 1;

FIG. 3 is a side view of the table top surface and edge shown in FIG. 1;

FIG. 4 is a lower perspective view of the table top surface and edge shown in FIG. 1; and,

FIG. 5 is a cross-sectional side view along lines 5-5 of the table top surface and edge shown in FIG. 1.

The broken lines shown in the figures are for illustrative purposes only and form no part of the claimed design.

1 Claim, 4 Drawing Sheets

FIG. 1

Title: PORTION OF A TABLE TOP
Inventor: David C. Winter
Docket: 15499.5002

FIG. 2

FIG. 3

FIG. 4

FIG. 5

UNITED STATES PATENT AND TRADEMARK OFFICE
CERTIFICATE OF CORRECTION

PATENT NO. : D659,450 S
APPLICATION NO. : 29/390471
DATED : May 15, 2012
INVENTOR(S) : Winter et al.

Page 1 of 2

It is certified that error appears in the above-identified patent and that said Letters Patent is hereby corrected as shown below:

In the drawings, Fig. 2 of sheet 2 of 4 should be deleted and replaced with the attached corrected Fig. 2.

Signed and Sealed this
Seventh Day of August, 2012

David J. Kappos
